UNITED STATES PATENT OFFICE.

ADRIAN H. AUSTIN, OF NEW YORK, N. Y.

DESIGN FOR ROSETTES.

Specification forming part of Design No. 7,629, dated August 11 1874; application filed June 24, 1874.
[Term of Patent 3½ years.]

To all whom it may concern:

Be it known that I, ADRIAN H. AUSTIN, of New York, in the county of New York and State of New York, have invented certain new and useful Improvements in Designs for Rosettes; and I do hereby declare the following to be a full, clear, and exact description of the invention, such as will enable others skilled in the art to which it pertains to make and use it, reference being had to the accompanying drawings, which form part of this specification.

The nature of my invention relates to an improvement in designs for rosettes; and it consists in the arrangement and configuration of parts, which will be more fully described hereafter, whereby a new and beautiful design for rosettes for shoes and other articles is produced.

The accompanying drawing represents my invention.

a represents a circular piece of any suitable kind of material, having its edge cut and scalloped, and which forms the base of the rosette. Upon the top of this base are placed other

pieces, *c*, arranged relatively, as represented. These pieces *c* are of different sizes, the lowest one being the largest, so as to display each one to the best advantage. On top of the pieces *c* is an ornamental button, *e*, the whole resembling a rose in configuration. Under the base *a* are placed leaves *g*, suitably shaped and showing their veins, and which project out and form an ornamental background for the rosette proper.

The parts above described may be made from any suitable kind of material, and the rosette may be used to ornament shoes of all kinds, harness, and other articles as may be desired.

Having thus described my invention, I claim—

A design for rosettes, substantially as shown and described.

In testimony that I claim the foregoing I have hereunto set my hand.

ADRIAN H. AUSTIN.
